UNITED STATES PATENT OFFICE.

DE WITT C. HARLOW, OF CHIPPEWA FALLS, WISCONSIN.

VALVE FOR STEAM-ENGINES.

SPECIFICATION forming part of Letters Patent No. 313,496, dated March 10, 1885.

Application filed January 23, 1884. (No model.)

To all whom it may concern:

Be it known that I, DE WITT C. HARLOW, a citizen of the United States, residing at Chippewa Falls, in the county of Chippewa and State of Wisconsin, have invented a new and useful Valve, of which the following, in connection with the annexed drawings, is a specification.

My invention relates to oscillating conical valves used in steam-engines instead of the slide-valve; and it consists in novel means, hereinafter fully described and specifically claimed, by which said valve is balanced and made to wear evenly and for a longer period of time than the unbalanced valves of the above-named class.

In the accompanying drawings, Figure 1 is a horizontal longitudinal central section of a steam-cylinder provided with four of my balanced valves. Fig. 2 is a vertical central section through two opposite valves at one end of the steam-cylinder. Fig. 3 is a perspective view of the said valve. Fig. 4 is a section of the valve and valve-seat in the line of the supply-passage of the balancing steam, and Fig. 5 is a section in the line of the exhaust-passage of the balancing steam.

A represents a steam-cylinder; B, a piston; C C' C² C³, steam and exhaust chests, and D D' D² D³ steam-valves of like construction. Steam-ports a a' a² a³ are provided at the ends of the steam-cylinder for the purpose of admitting and exhausting steam, as will be seen. The steam-chests C C' may be united by a pipe, C⁵, which connects with a supply-pipe, C⁴, and the exhaust-chests C² C³ may be similarly united and connected with an exhaust-pipe. The steam and exhaust chests are each provided with a conical shell-bearing, c, into which the conical valves D D' D² D³ are fitted. The ports a a' a² a³ open into said shell-bearings, as shown. Two diametrically-opposite ports, c', standing at right angles to the ports a a' a² a³, are provided in the shell-bearings c for the purpose of letting steam into the valve. The valves are provided with passages d and d', standing at right angles to one another and having the same area as the ports c' a, and when the valves are fully open for the purpose 50 of admitting steam to the engine the passages

d tally with the ports c', and the passages d' tally with the ports a.

At the back of the passages d a small passage, d², is provided, which leads to a depression, c², in the inner surface of the shell-bearing c. 55 This depression is of the same area as the passage d' and stands opposite the ports a a' a² a³. The steam is conducted away from the depression c² by a passage, d³, in the conical valve, which passage, at every oscillation of the valve, 60 tallies with a passage, a⁴, in the ports a a' a² a³. The said passage d³ connects with a depression, d⁴, on the outer surface of the conical valve, which depression serves to establish communication between the passages d³ and a⁴ before 65 they stand in line with each other, whereby steam communication is established between the cylinder and the depression c² as soon as the supply-steam is cut off from the steam-cylinder.

In the exhaust-valves D² D³ the action of the steam reverses the above-described operation, and the balancing steam is admitted through the passages a⁴ d³ into the depression c² while the exhaust-port of the cylinder is 70 closed up by the valve, and the steam is exhausted from the depression c² through the passage a⁴ while the exhaust-valve is open and permits the steam to leave the cylinder. The valves D D' D² D³ are provided with shanks d⁵, 80 to which arms d⁶ are attached for the purpose of operating them. The valves are longitudinally adjusted by means of and between set-screws E. These set-screws are secured in plates or brackets e e', attached to the steam-chests, and by means of these set-screws the valves can be so adjusted that the friction and wear of the valves and valve-seats are reduced to a minimum.

In the drawings the ports of the cylinder, 90 valve, and valve-seats are strengthened by stays f; but this means of strengthening may be omitted in smaller engines.

The cylinder shown in the drawings is of unusual length, owing to the construction of 95 the steam-chests, and therefore the cylinder-heads are of suitable form in order to fit the long recesses of the cylinder and provide proper end abutments in line with the cylinder-ports. The steam-chests may be bolted to the 100

cylinder, or they may be cast solid with the same; but in the latter case the end portions or tops of the steam-chests must be removable in order to admit tools for finishing the ports 5 in the shell-bearings *c*.

It will be seen that my valves are at all positions balanced, inasmuch as there is steam admitted into the depressions *c*² of the valves D D' D² D³ as long as there is steam in the cylinder, and as soon as steam is exhausted from the cylinder the depressions *c*² are also exhausted; and inasmuch as the ports *c*² are diametrically opposite each other and the steam-passages *d* in the valves occupy a central position in the valves, the valves are balanced 15 in a line parallel with the cylinder.

I am aware that oscillating conical steam-balanced valves with longitudinal or axial adjustment have been in use; but my invention 20 is essentially different from all of them inasmuch as, first, the ports of my valve are, as shown and described, peculiarly constructed and the ends of the valve are closed and free from binding contact upon the ends of the 25 steam-chest, while the brackets *e e'*, holding the adjusting-screws *E*, do not require packing around the valve-stem, and may be so constructed as to admit the atmospheric air to the said ends of the valve and permit ready 30 access to the valve and its chest; second, the set-screws *E* are so isolated as not to be exposed to the corroding action of steam, while they are accessible from the outside of the chest, and by this construction the longitudinal 35 adjustment of the valve by means of the set-screws *E*, which becomes necessary from time to time, is convenient and positive, and any adjustment necessary can be effected immediately and with very little labor. With 40 known constructions requiring packing around the valve-stem, the central adjustment of the valve is often interfered with by reason of the packing fitting very tight and the valve being more or less forced from its central position by non-uniform settling of the packing 45

material, and owing to this the valve becomes leaky unless it is forced into its valve-seat with a much greater strain than is required with my arrangement, which dispenses with the use of packing. When set-screws for longitudinal adjustment of such valves are exposed to steam, they corrode and diminish in length, and this necessitates frequent adjustment; and as it is necessary, in order to get access to these set-screws, to often remove portions of the 55 steam-engine, much delay and expenditure of extra labor are experienced.

What I claim as my invention, and desire to secure by Letters Patent, is—

1. An oscillating hollow conical valve, *D*, 60 having solid closed ends, passages *d d' d*³, and a stem, *d*⁵, at one end, in combination with a suitable valve-seat having open ends, a passage, *a*⁴, a depression, *c*², and ports *a a' a*² and *c c' a*³, and with brackets *e e'*, and central outside set-screws, *E*, for longitudinal adjustment of the valve, substantially as described. 65

2. An oscillating valve receiving steam by means of two diametrically-opposite ports and delivering it by means of one port standing at 70 a right angle to the receiving-ports, in combination with a valve-seat having three similar ports, two diametrically opposite and communicating with the steam-chest and one at a right angle communicating with the steam-cylinder, substantially as described. 75

3. The combination of an oscillating valve having two diametrically-opposite receiving-ports and one delivering-port at a right angle thereto, with a suitable valve-seat having similar ports, and an automatic balancing steam-chamber opposite its delivering-port, said balancing steam-chamber having alternate connection with the valve-ports and the steam-cylinder, substantially as and for the purpose 85 described. 8c

DE WITT C. HARLOW.
